UNITED STATES PATENT OFFICE.

BENNO VOM EIGEN, OF NEWARK, NEW JERSEY, ASSIGNOR TO AUG. GOERTZ & CO., A CORPORATION OF NEW JERSEY.

BAG-FRAME.

1,153,652.

Specification of Letters Patent. Patented Sept. 14, 1915.

Application filed February 2, 1911. Serial No. 606,071.

To all whom it may concern:

Be it known that I, BENNO VOM EIGEN, a citizen of the United States, residing at Newark, in the county of Essex and State of New Jersey, have invented certain new and useful Improvements in Bag-Frames; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention has reference, generally, to that class of frame-sections which are used with bags, satchels, and the like; and, the present invention relates, more particularly, to a novel means for rigidly connecting the miter-joints in the corners of the main or central member and the leg-members of a one-piece bag-frame section.

The invention has for its principal object to provide a novel and simply constructed as well as a neat and a cheap binding or connecting means, in the form of a strap adapted to be arranged across the miter-joints in the corners of the main or central member and the leg-members of the bag-frame section, whereby the edge-portions of the joints are rigidly and positively connected.

Other objects of this invention not at this time more particularly enumerated will be clearly obvious from the following detailed description of the present invention.

The invention is clearly illustrated in the accompanying drawings, in which:

Figure 1 is a front elevation of a bag-frame section made according to and embodying the principles of the present invention; and Fig. 2 is a view of the inner face-portions of the frame-section, showing more particularly the tying or binding straps arranged across the miter-joints for the angle-portions of the respective members of the frame-section. Fig. 3 is an enlarged view of one of the angle-portions of the connected members of the frame-section, said view showing, more particularly, one of the miter-joints with the tying or binding strap omitted from said view; and Fig. 4 is a cross-section taken on line 4—4 in said Fig. 2, looking in the direction of the arrow *w*, said view also being made on an enlarged

scale. Fig. 5 is a side view of one of said tying or binding straps made on an enlarged scale; and Fig. 6 is a cross-section of the same, said section being taken on line 6—6 in said Fig. 5.

Similar characters of reference are employed in all of the above described views, to indicate corresponding parts.

Referring now to the several figures of the drawings, the reference-character 1 indicates a frame-section showing one embodiment of the principles of the present invention, the said frame-section comprising a main or central member 2 and a pair of leg-members 3. Extending at right angles from one of the marginal edge-portions of the member 2 is a flange or projection 4, and similarly extending at right angles from one of the marginal edge-portions of the leg-members 3 are flanges or projections 5, said flanges or projections 5 being respectively integrally connected with the end-portions of the flange or projection 4, as at 6, all of said parts being made from a single piece of metal, and being bent in the manner illustrated in the several figures of the drawings. In the manufacture of the frame-section the adjacent end-portions of the respective members 2 and 3 are angularly cut-away, so as to provide the angles of the frame-section with the miter-joints 7 extending from the connecting portions 6 of the flanges or projections 4 and 5, in the manner represented in Figs. 1, 2 and 3 of the drawings.

As shown more particularly in Fig. 3 of the drawings, the end-portions of the main or central member 2 are provided near the miter-joints 7 with suitably formed holes or perforations 8, preferably of rectangular configuration, as illustrated; and each leg-member 3 is also provided at its end-portion near the miter-joint with a similarly formed hole or perforation 9.

Extending across each miter-joint is a tying or binding-strap 10, the upper surface of the body of said strap being preferably rounded off, as at 11, and the flat face 12 of said strap having extending therefrom a pair of rivet-lugs or studs 13 and 14. These lugs or studs, in cross-section, are of the same conformation as the holes or perforations 8 and 9, and when the strap 10 is secured in place across a miter-joint 7, the stud or lug 13 is inserted in the hole or per-

110

foration 8, and the stud or lug 14 is likewise inserted in the hole or perforation 9. By means of the proper tool, the free projecting ends of said lugs or studs 13 and 14 are then pressed down into the metal face-
5 portions of the said main or central member 2 and the respective leg-members, as clearly shown in Figs. 1 and 4 of the drawings, the surface-portions of the frame-sec-
10 tion and the upset ends of said lugs or studs then being rendered smooth by means of a burnishing or other suitable tool, so as to provide perfectly smooth surface-portions at the corners of the frame-section. By this
15 means a simple and cheaply constructed device has been provided for readily and quickly uniting the angular edge-portions of the main or central member 2 to the angular edge-portions of the respective leg-
20 members 3, so as to produce a perfectly closed and a rigidly connected miter-joint at each corner of this bag-frame section.

I claim:

25 A bag-frame section comprising a main central member having angular marginal end-portions, and a pair of leg-members, each leg-member having an angular marginal end-portion adjacent to and abutting upon an angular marginal end-portion of
30 the main central member, said angular

marginal end-portions forming a straight and uninterrupted miter-joint, the said abutting end-portions of said main central member and said leg-member being provided with perforations, a flange extending at a 35 right angle from said main central member, a flange extending at a right angle from each leg-member, the flanges of said leg-members being integrally connected with the flange of said main central member, and a narrow tie-strap extending diagonally 40 across said miter-joint, stud-like rivet-posts extending from said tie-strap, said posts being fitted into the said perforations in the main central member and the respective leg-
45 members and riveted flush with the exterior surface-portions of said main central member and said leg-members, so as to entirely close up said perforations and provide smooth and unobstructed outer surface-portions, substantially as and for the purposes 50 set forth.

In testimony, that I claim the invention set forth above I have hereunto set my hand this 30th day of January, 1911.

BENNO VOM EIGEN.
